UNITED STATES PATENT OFFICE

MICHAEL A. ROLLMAN, OF MOUNT JOY, PENNSYLVANIA

SADIRON STAND

Application filed May 8, 1928. Serial No. 276,140.

The object of this invention is to provide an inexpensively-constructed stand which is adapted to support a sad iron when not in use, the desirable form being the one which is reversible, one, the upper, side being adapted for supporting the iron from time to time during the ironing operation, and the other, lower, side being adapted to support the iron when the ironing work is finished and the iron is put away, as more fully hereinafter set forth.

In the drawing annexed,

Fig. 1 is a perspective view of one form of my device;
15 Fig. 2 is a longitudinal sectional view on the line 2—2 of Fig. 1;

Fig. 3 is a transverse sectional view on the line 3—3 of Fig. 1;

Figs. 4 and 5 are sectional views showing 20 modified forms of the device.

Referring to Figs. 1, 2 and 3, 10 designates a metallic plate having a shape substantially the same as the bottom of the iron, but larger than the same. This plate is provided all 25 around its edge with a downwardly-turned flange 11 which is adapted to rest on the table and thus support the plate 10 a distance above the table. This flange 11 is in turn provided with an outwardly-extending 30 flange 12 at the forward end as well as at the rear corners to provide feet. For stiffening the plate, to thus enable me to use a thin metal sheet, I provide a bead 13' extending around the point and the sides of 35 the plate, this bead being desirably omitted at the rear end of the stand.

On the upper face of the plate 10 is a series of upstanding disks of insulating material 13, such as asbestos, five of these disks 40 being shown in the present instance. These disks are fastened to the plate 10 by being crimped in holes therein, the crimping flanges being shown at 14. Secured by rivets 15 to the under face of the plate 10 is an insulating-plate 16, which is substantially the same 45 in area as the bottom face of the plate 10 and is shaped to fit against the rim-flange 11. The lower faces of the knobs or disks 13 abut against the adjacent face of this insulating-sheet 16. The insulating-disks 13 sup-

port the iron free of the metal plate 10 and also the bead 13'; these disks being thick enough to thus keep the iron out of contact with said bead 13'. These supporting-disks 13 are used to support the iron from time 55 to time during the ironing operation. When the ironing is finished and it is desirable to put the iron away on a shelf or other support, the stand is reversed, as shown in Figs. 2 and 3, to thus form a tray for the iron, the iron resting upon the insulating-sheet 16. In this way, the hot iron will be kept away from the metal not only during the ironing operation, but after it is stored away, thus decreasing fire risk to a minimum. Also, when 65 the iron is put in the tray and the tray is put away, the disks 13 form legs or feet which raise the metal part of the device above the supporting surface to thus avoid all danger of fire from a highly-heated iron. 70 The rivets 15 are desirably counter-sunk in the insulating-plate 16 to avoid direct communication of heat from the iron to the plate 10.

In Fig. 4, the disks 14 are secured directly 75 to the top face of the plate 10 each by a rivet 17, to thus avoid the necessity of cutting large holes in the plate 10 and also the use of the crimping-flanges 14. These rivets 17 also avoid the necessity of using the 80 separate rivets 15.

In Fig. 5, I show insulating abutments or disks 18 substituted for the insulating-plate 16, to thus economize in the use of insulating material. In this construction, Fig. 5, it will 85 be observed that I also avoid the use of the crimping-flanges 14 and, as in Fig. 4, I provide a firmer support for both the disks 14 and for the insulating medium located on the opposite surface of the plate 10. 90

What I claim as new is:

1. A sad-iron stand consisting of a single sheet of thin metal of substantially the shape of the bottom of the iron but larger in area than the same, formed with a depending 95 apron or flange extending entirely around the edge of the sheet and provided at its forward end as well as its two rear corners with lateral extensions forming feet, said sheet being also formed around its sides and for- 100

ward edge with an upstanding bead, each face of said sheet being provided with insulating material to prevent contact of the bottom of the iron with the sheet, thereby providing a device which in one position will serve as an insulating stand and in the reverse position will provide an insulating tray.

2. A sad-iron stand consisting of a plate of metal substantially the shape of the bottom of the iron but larger in area than the same, formed with a depending apron extending entirely around the edge of the sheet, each face of said sheet being provided with insulating material, and rivets fastening said insulating material to the respective faces of said sheet, said rivets extending through the insulating material and the intermediate sheet and being counter-sunk in the insulating material.

20 3. A sad-iron stand consisting of a plate of metal substantially the shape of the bottom of the iron but larger in area than the same, formed with a depending apron extending entirely around the edge of the sheet, 25 each face of said sheet being provided with insulating material in the form of disks clamped to the opposite faces of said plate by rivets extending through the disks and the intermediate plate and having their heads 30 counter-sunk in the disks.

In testimony whereof I hereunto affix my signature.

MICHAEL A. ROLLMAN.
